JOINER SHINGLE

Art G. Goslin, Battle Creek, Mich., assignor to
Sheriff-Goslin Co., Battle Creek, Mich., a corporation of Michigan

Application March 25, 1936, Serial No. 70,726

12 Claims. (Cl. 108—8)

My present invention relates broadly to coverings for surfaces such as the roofs and side walls of buildings. In its specific phase my invention relates to a joiner shingle which is preferably of a rigid or semi-rigid construction.

The present application is a continuation-in-part of my co-pending patent application Serial No. 48,169, filed Nov. 4, 1935.

In the past many forms of surface coverings have appeared on the market and have become widely known and used. The most commonly known materials that fall in the rigid or semi-rigid group of this class, outside of wood shingles, are those that can be grouped under the headings of slate, tile, and asbestos shingles. The latter, particularly, has been made up in many different forms for roof use, and perhaps two of the commonest forms of same are those known as the diamond pattern shingle and the dutch-lap shingle. Both of these shingles require the use of a storm nail to secure the lower exposed corner of the shingle against warping and blowing up. The use of a storm nail requires the shingle to be punched for it, the head of the nail inserted under the abutting edges of two adjacent shingles, the laying of the top shingle so that the hole punched in its lower corner receives the projecting end of the storm nail, and lastly the bending over of the storm nail to hold down the lower corner of the top shingle.

Attempts have been made with more or less success to use slate, tile, and asbestos shingles for siding buildings. One common form of the asbestos shingles used for this purpose is about twice as long as it is wide, and when laid in overlapping courses, the vertical edge of one shingle butts up against the vertical edge of the next adjacent shingle in the same course without any overlap. This type of construction is subject to leakage at the points where the shingles butt up against each other. To avoid this leakage it has been proposed in U. S. Patent No. 1,358,863 to punch the shingles along their vertical abutting edges, and then lay a course of shingles over the joint in manner such that the punched holes can be utilized for nailing the superimposed shingles in place. The more commonly used form of making these joints water resistant, however, is to first cover the surface to be sided, with a waterproof material such as single ply roll roofing, or else to place a waterproof strip of such material under each joint of the siding shingles as they

are laid. All three of these procedures obviously are time consuming and expensive.

The common form of asbestos siding shingles, described above, are punched with holes arranged along the upper edge for nailing under the horizontal lap formed by the overlapping of the course above. Another row of holes is punched near the bottom edge of the shingle just above the upper edge of the lower shingle course. The nails used in this row of holes for holding the butt of the shingle down, are exposed to the weather, which I have found tends to cause the nails to gradually draw and the shingles to become loose and rattle. Special nails must also be used, since otherwise they will corrode and cause discoloration streaks to appear below each nail. At the present plated nails are used for this purpose, but even they are none too good, as it is well known that plating wears off in a relatively short time and in fact may be damaged due to the driving of the nails. To reduce to a minimum the corrosion of the nails with resultant discoloration streaking of the shingles, plated nails have been made with a bronze shank and head. When considering the number of exposed nails used per shingle under the common practice at this time, it at once becomes obvious that the use of plated bronze nails is a relatively expensive procedure.

My present invention involves a new type of surface covering element, preferably in rigid or semi-rigid form, as well as the procedure of making same, which obviates many of the difficulties encountered in connection with the present day surface coverings.

Accordingly, among the objects of the present invention is the provision of a structure that eliminates the use of storm nails, and the punching necessary in connection therewith. Another object is to eliminate the necessity of placing a waterproof strip under the vertical joints of shingles laid edge to edge in the form of siding. A further object is to provide a simple vertical lap at the side joints of shingles used in the form of siding. A further object is to eliminate the necessity of using exposed nailing on the siding shingles. A further object is to provide a joiner shingle which may be provided with one exposed nail near its butt edge. A further object is to provide a joiner shingle which has no exposed nails, but is provided with an interlocking means whereby the time consumed in laying same is materially reduced. A still further object is to provide an assembly that is neat in appearance, easy to lay, and wherein the joiner shingle acts to supplement the regular shingles so that a

smaller number of the latter will suffice to cover a given size area. Other objects and advantages will appear as the description proceeds.

To the accomplishment of the foregoing and related ends, the invention, then, consists of the articles and construction hereinafter fully described and particularly pointed out in the claims, the annexed drawing, and the following description setting forth in detail several modes of carrying out the invention, such disclosed modes illustrating, however, but several of the various ways in which the principle of the invention may be used.

In the said annexed drawing:—

15 Fig. 1 shows one form of my joinder shingle; Fig. 2 is an enlarged sectional view of the joinder shingle taken along line 2-2 of Fig. 1; Fig. 3 shows another form of my joinder shingle; Fig. 4 illustrates in diagrammatic manner the use of 20 one form of my joinder shingle; and Fig. 5 illustrates in like manner the use of another form of my joinder shingle.

In the drawing I have shown the preferred embodiment of my invention in diagrammatic manner, and in connection with shingles or siding as a simplest form of illustration. Two forms of my joiner shingle are shown, as well as assembly views wherein the use of both are illustrated. The joiner shingle having the interlocking means obviates the necessity of storm nails, punching for storm nails, waterproofed strips under joints, and all exposed nailing on the shingles to be joined. The other joiner shingle shown has the same advantages, but is cheaper to construct by virtue of using one exposed nail in place of the interlocking means. By joiner shingle I mean a shingle adapted to join other shingles or surface covering elements together, where the shingles or the like to be joined, or at least part of them, vary in shape, size, or some other characteristic from the joiner shingle itself.

Referring more particularly to the drawing, Fig. 1 illustrates one form of my joinder shingle. This joinder shingle 1 is provided with a beveled upper edge 2, and has on its under face near the butt edge thereof a projecting rib 3 having an under-cut face 4 adapted to engage with the beveled upper edge 2 of a like adjacent joinder shingle in the next lower course, as is shown in Fig. 4. This projecting rib 3 is preferably of a length that is approximately the same as, or narrower than the width of the top edge of the shingle between the notches, and preferably so centered on the shingle that it will satisfactorily engage with the beveled top edge of the next lower adjacent joinder shingle. Holes 5 are provided near the beveled upper edge 2 of the joinder shingle whereby the same may be fastened by suitable nails or the like to the surface being covered. The size of the joinder shingle will depend largely upon the size of the shingles to be joined. Where such shingles are twelve inches high and twenty-four inches long, I prefer to use a joinder shingle that is twelve and a half inches high and twelve inches wide though the invention is not limited to a shingle of such specific size. The extra one half inch in height will provide sufficient overlap at the bottom of the joinder shingle to satisfactorily eliminate leakage when used on a vertical surface, though a greater overlap may be required when used on a lower pitch surface. The use of joinder shingles with the recesses which produce an open upper corner profile adapted to receive the full size lower adjacent corners of the next higher course of siding.

shingles, while extending below the bottom of the siding shingles in the course being joined, and overlapping the next lower adjacent joiner shingle, provides covered horizontal joints under the joiner shingles and at the same time eliminates all exposed open vertical butted joints. The two upper corners of the joiner shingle are notched out, so as to permit the lower corners of the next higher course of shingles that are to be joined, to slip into these notched out corners. The size 10 that the notches are to be made depends upon how much of a maximum overlap of the side edges of the shingles for waterproofing purposes is desired, as well as the amount of overlap of one joiner shingle over the other. I have found 15 that a notch which is one and a half inches wide and one and a half inches deep will satisfy most requirements and give a good side lap over the shingles to be joined. Where this size notch is used on an eleven inch width joiner shingle, or 20 if a twelve inch joiner shingle is used and the notches made two inches wide, then when laid on a surface having sixteen inch center spaced studding, the shingles as well as the joiner shingles may be laid so that their centers fall on the center of the studding members, thus permitting effective use of long nails at the center of the shingles and joiner shingles. The size of the notch, however, may be varied at will to suit the 25 particular conditions at hand, and as the pitch of the surface to be covered decreases, in general the notches should be enlarged so as to provide a greater overlap, which will counteract the tendency of water to creep or flow under the shingle. The shape of the notches may also vary so as to fit the particular shingles to be joined, the bottom of the notch may for instance be flat, V-shaped, S-shaped or the like, and the notch may 30 also as the case requires, be square, rectangular, triangular, or the like, and the notch on one side of the joiner shingle may be deeper than the other so as to better fit shingles that have an irregular bottom edge. In some cases it may be desirable to under-cut the under face of the shingle at the laps in order to prevent capillary 35 flow of water thereunder. In other words the difficulties encountered due to the drawing of exposed nails, and leakage at the vertical joints of shingles butted together as hereinbefore described, but without waterproof stripping, can be easily overcome through the use of a joiner shingle as is shown in Figures 1 and 2, the latter 40 of which shows the arrangement of the bevels.

The notches in the top of the shingle may be formed in various ways, either by hand or automatically by machine. The shingle may be cut, formed, or molded initially with the holes and notched out corners at the desired places, or in case of asbestos shingles that are first pressed and cured, and then later trimmed to size, the shingle at the time of trimming, if desired, can have its corners notched out and the desired holes punched, thus producing the completed joiner shingle. 55 60

Fig. 4 shows a typical installation using my joiner shingle. After the lower course has been laid with a joiner shingle 1 in place, then the joiner shingle in the next higher course fits over the lower joiner shingle, so that the under-cut face 4 of the projecting rib 3 interlocks with the beveled under edge 2 of the lower joiner shingle. Thus with shingles 6 and 7 in place and nailed along their upper edge, and along the sides if desired, though the latter is not necessary in the case of rigid or semi-rigid shingles, and the

punching for the vertical rows of holes may be eliminated, the nailing of the upper joiner shingle along its upper edge acts to lock the whole shingle structure in place without the necessity 5 of exposed nails, or weatherproofed strips under the vertical joints, since the edges 8 and 9 of the joiner shingle which overlap the adjacent edges of shingles 6 and 7, act not only to hold the shingles firmly in place, but also to form an 10 overlapped joint, which substantially eliminates leakage.

While I have shown in my drawing, a projecting rib 3 with an under-cut face 4, and an interlocking upper beveled edge 2 having an angle of 15 45°, such is not the only angle that can be used since obviously various angles are applicable, so long as a locking joint is obtained. Moreover, instead of a beveled joint, I contemplate as within 20 the scope of my invention the use of other equivalent joints, such as a rib in the form of a channel like trough which may be of metal or other rigid or semi-rigid material, thus permitting the elimination of beveling the edge of the shingle or siding that is to mesh therewith. The projecting 25 rib may be made of various materials, such as metal, wood, fibre, asbestos-concrete, or the like. I prefer, however, to use the same kind of material that is used in the shingle itself, since the contraction and expansion in such case will coincide with that of the shingle. The projecting rib, moreover, may be made as an integral part 30 of the shingle, or may be fastened thereon in conventional manner as, for instance, by the use of embedded rivets, or gluing or cementing same in 35 place with a water-insoluble material.

Where it is desired to take advantage of my joiner shingle with its notched out corners, and nail holes 5 along its upper edge, but the interlocking is not desired, then the form shown in 40 Fig. 3 may be resorted to. In the place of the interlocking means is used holes 10 and 11. These two holes are so located that when the siding shingle is laid with joiner shingles in place hole 10 of one joiner shingle will come directly under 45 hole 11 of the next higher joiner shingle. This type of joiner shingle thus permits the siding shingles to be laid without exposed nails, and the joiner shingle to be laid with but one exposed nail. Hole 11 is preferably made of such a size 50 that it is approximately the same size or just slightly larger than the shank of the holding means or nail to be driven through it. Hole 10 on the other hand I prefer to make slightly larger than hole 11 to facilitate lining up the two holes 55 when the nail is to be driven. In order to waterproof the hole 10 to prevent leakage through it from hole 11 above I prefer to fill the hole with pitch, melted asphalt, mastic, putty, flashing compound, a rubber bushing, or any other suitable material having long life waterproofing characteristics. It is not intended to limit the invention to those particular waterproofing materials named, but rather any means for waterproofing this joint is contemplated, even to the 60 use of a thin sheet of rubber or corrosion resistant relatively soft metal between the two joiner shingles with the nail or other means passing therethrough to hold the butt of the top joiner shingle in place. Fig. 5 shows an assembly of shingles utilizing the joiner shingle shown in Fig. 3, hole 10 of the upper joiner shingle 65 being shown filled with waterproofing material 12 as described above.

Other modes and means of applying the principle of my invention may be employed instead of 70

those explained, change being made as regards the article and construction herein disclosed, provided the means and modes stated by any of the following claims or the equivalent of such stated means and modes be employed. 75

I therefore particularly point out and distinctly claim as my invention:—

1. A joiner shingle which is adapted to be laid with its upper edge approximately in line with the upper edge of the adjacent shingles of different type to be joined in the same course while overlapping the adjacent side edges thereof, and at the same time adapted to extend below the lower edges of said adjacent shingles of different type and to overlap the upper end of the adjacent like joiner shingle of the next lower course to eliminate exposed open vertical butted joints and provide a covered horizontal joint, said joiner shingle having its upper corners cut away to provide a substantially rectangular open corner profile with the bottom of said cut away portion substantially perpendicular to the vertical center line of the shingle so that the full size substantially square cut lower adjacent corner of each of said adjacent shingles of different type of the next higher course will fit therewith, said joiner shingle being provided on its upper edge between the cut away corners with openings adapted for use in fastening same to a suitable surface, and also with means at its upper and lower edges to facilitate anchoring one joiner shingle to another when they are laid in courses, one above the other.

2. A covering for a wall or roof consisting of a plurality of elements secured to the surface to be covered, and disposed in a downwardly overlapping relation, said elements comprising substantially rectangular square cornered shingles laid in courses and joined together at their side edges by means of joiner shingles having completely notched out upper corners in manner producing a substantially rectangular open upper corner profile adapted to receive the full size lower corners of the shingles of the next higher course to be joined, said joiner shingles being of such a size that each extends below the bottom edges of the shingles in the course it joins, overlaps the top of the next lower joiner shingle and at the same time overlaps the side edges of the adjacent shingles in the same course to provide substantially water-tight joints, and means for fastening the shingles and joiner shingles to the surface being covered.

3. In a covering for a surface, the employment of substantially rectangular square cornered shingles laid in substantially spaced rows, the bottom of one overlapping the top of the next lower adjacent shingle in the row, each of said shingles being nailed in place across the top at a point which will be covered by the overlap of the next higher shingle; in combination with joiner shingles disposed in rows alternating with said shingles, for covering the spaces therebetween and completing the courses thereof, each joiner shingle having its upper corners recessed so as to produce an open upper corner profile adapted to receive the full size lower adjacent substantially square corners of the next higher course of shingles and permit said joiner shingle to overlap the side edges of the shingles in the same course, said joiner shingle extending below the bottom line of the shingles in the same course so as to provide a covered horizontal joint with the next lower joiner shingle and at the same time to eliminate exposed open vertical butted joints, 75

- receptacles on the upper end of said joiner shingle between said recesses adapted to receive a suitable water-tight means for fastening same to the surface being covered, and means at the top and bottom of said joiner shingle adapted for use in holding the bottom of one joiner shingle against the top of the next adjacent lower joiner shingle.
4. In a covering for a surface, the employment of substantially square cornered rectangular shingles laid in substantially spaced rows, the bottom of one overlapping the top of the next lower adjacent shingle in the row, each of said shingles being nailed in place across the top at a point which will be covered by the overlap of the next higher shingle; in combination with joiner shingles disposed in rows alternating with said shingles, for covering the spaces therebetween and completing the courses thereof, each joiner shingle having its upper corners recessed so as to produce a substantially rectangular open upper corner profile adapted to receive the full size lower adjacent corners of the next higher course of shingles and permit said joiner shingle to overlap the side edges of the shingles in the same course, said joiner shingle extending below the bottom line of the shingles in the same course so as to provide a covered horizontal joint with the next lower joiner shingle and at the same time to eliminate exposed open vertical butted joints, receptacles on the upper end of said joiner shingle between said recesses adapted to receive a suitable means for fastening same to the surface being covered, and an opening at the top, and one in alignment therewith at the bottom of said joiner shingle so that when said joiner shingles are laid one above another in courses, the hole in the bottom of one will coincide with the aligned hole in top of the next adjacent lower joiner shingle.
40. 5. A joiner shingle which is adapted to be laid with its upper edge approximately in line with the upper edge of the adjacent shingles of different type to be joined in the same course while overlapping the adjacent side edges thereof, and at the same time adapted to extend below the lower edges of said adjacent shingles of different type and to overlap the upper end of the adjacent like joiner shingle of the next lower course to eliminate exposed open vertical butted joints and provide a covered horizontal joint, said joiner shingle having its upper corners cut away to provide a substantially rectangular open corner profile with the bottom of said cut away portion substantially perpendicular to the vertical center line of the shingle so that the full size substantially square cut lower adjacent corner of each of said adjacent shingles of different type of the next higher course will fit therewith, said joiner shingle being provided on its upper edge between the cut away corners with openings adapted for use in fastening same to a suitable surface, and also with an opening at the top and one at the bottom thereof in alignment so that when laid in courses the hole in the bottom of one joiner shingle will coincide with the hole in the top of the next adjacent lower joiner shingle.
60. 6. A joiner shingle which is adapted to be laid with its upper edge approximately in line with the upper edge of the adjacent shingles of different type to be joined in the same course while overlapping the adjacent side edges thereof, and at the same time adapted to extend below the lower edges of said adjacent shingles of different type and to overlap the upper end of the adjacent like joiner shingle of the next lower course to eliminate exposed open vertical butted joints and provide a covered horizontal joint, said joiner shingle having its upper corners cut away to provide a substantially rectangular open corner profile with the bottom of said cut away portion substantially perpendicular to the vertical center line of the shingle so that the full size substantially square cut lower adjacent corner of each of said adjacent shingles of different type of the next higher course will fit therewith, said joiner shingle being provided on its upper edge between the cut away corners with openings adapted for use in fastening same to a suitable surface, and also with an opening at the top and one at the bottom thereof in alignment so that when laid in courses the hole in the bottom of one joiner shingle will coincide with the hole in the top of the next adjacent lower joiner shingle.
70. 7. A rigid or semi-rigid flat and beadless joiner shingle that has its two upper corners suitably notched out to produce an open upper corner profile, and which has suitable holes formed adjacent its upper edge between the notches as well as one adjacent the bottom of the shingle, the bottom hole being in alignment with one of the top holes so that when the shingles are laid in a single shingle width row and in prescribed overlapping manner one above the other the two holes will coincide to permit a nail or the like to be driven therethrough to fasten the butt of the joiner shingle in place, the coinciding hole in the joiner shingle top being substantially larger than the bottom hole and filled with a plastic waterproofing material.
8. In siding for building walls or the like, the employment of substantially rectangularly siding shingles laid in substantially spaced rows, the bottom of one overlapping the top of the next lower adjacent shingle in the row, each of said siding shingles being nailed in place along its side edges and also across the top at a point which will be covered by the overlap of the next higher siding shingle; in combination with joiner shingles disposed in rows alternating with said siding shingles, for covering the spaces therebetween and completing the courses thereof, each joiner shingle having its upper corners recessed so as to produce an open upper corner profile adapted to receive the full size lower adjacent corners of the next higher course of siding shingles and permit said joiner shingle to overlap the side edges of the siding shingles in the same course and cover the nails in the edges thereof, said joiner shingle extending below the bottom line of the siding shingles in the same course so as to provide a covered horizontal joint with the next lower joiner shingle, and at the same time to eliminate exposed open vertical butted joints, receptacles on the upper end of said joiner shingle between said recesses, and under the overlap of the next higher joiner shingle, adapted to receive a means for fastening same to the surface being covered, separate aligned holes in the top and bottom of said joiner shingle adapted to coincide with like aligned holes in the adjacent joiner shingles when laid in courses and permit the anchoring of the bottom of the joiner shingle in place, the aligned hole in the top of the joiner shingle being substantially larger than the hole in the bottom of the joiner shingle and filled with a plastic waterproofing material.
9. A joiner shingle which is adapted to be laid

with its upper edge approximately in line with the upper edge of the adjacent shingles of different type to be joined in the same course while overlapping the adjacent side edges thereof, and at the same time adapted to extend below the lower edges of said adjacent shingles of different type and to overlap the upper end of the adjacent like joiner shingle of the next lower course to eliminate exposed open vertical butted joints and 5 provide a covered horizontal joint, said joiner shingle having its upper corners cut away to provide a substantially rectangular open corner profile with the bottom of said cut away portion substantially perpendicular to the vertical center 10 line of the shingle so that the full size substantially square cut lower adjacent corner of each of said adjacent shingles of different type of the next higher course will fit therewith, said joiner shingle being provided on its upper edge between 15 the cut away corners with openings adapted for use in fastening same to a suitable surface, and a projecting rib-like means, with an overhung portion, mounted on the under side of the joiner shingle at a point adjacent the butt thereof, the upper edge of said joiner shingle between said cut away portions being adapted to engage and lock with the projecting rib-like means on the like next higher joiner shingle when they are laid in courses, one above the other, said rib-like 20 means being of a width as a maximum equal to the space between the shingles of different type to be joined.

10. A joiner shingle which is adapted to be laid with its upper edge approximately in line with the upper edge of the adjacent shingles of different type to be joined in the same course while overlapping the adjacent side edges thereof, and at the same time adapted to extend below the lower edges of said adjacent shingles of different type 40 and to overlap the upper end of the adjacent like joiner shingle of the next lower course to eliminate exposed open vertical butted joints and provide a covered horizontal joint, said joiner shingle having its upper corners cut away to provide a substantially rectangular open corner profile with the bottom of said cut away portion substantially perpendicular to the vertical center line of the shingle so that the full size substantially square cut lower adjacent corner of each 45 of said adjacent shingles of different type of the next higher course will fit therewith, said joiner shingle being provided on its upper edge between the cut away corners with openings adapted for use in fastening same to a suitable surface, and projecting rib-like means mounted on the under 50 side of the joiner shingle at a point adjacent to but spaced from the butt thereof, said rib-like means being of a thickness approximately the same as that of the adjacent shingles of different 55 type to be joined and having a beveled undercut edge portion forming a socket at the edge thereof adjacent the butt of said joiner shingle, the upper edge of said joiner shingle between said cut away portions being beveled so as to fit the undercut portion of said rib-like means of the like next 60 higher joiner shingle and lock therewith to hold the bottom of one joiner shingle against the top of the next lower joiner shingle when the adjacent shingles of different type and joiner shingles are laid as described.

11. A covering for a wall or roof consisting of a plurality of elements secured to the surface to be covered, and disposed in a downwardly overlapping relation, said elements comprising substantially rectangular square cornered shingles laid in courses and joined together at their side edges by means of joiner shingles having completely notched out upper corners in manner producing a substantially rectangular open upper corner profile adapted to receive the full size lower corners of the shingles of the next higher course to be joined, said joiner shingles being of such a size that each extends below the bottom edges of the shingles in the course it joins, overlaps the top of the next lower joiner shingle and at the same time overlaps the side edges of the adjacent shingles in the same course to provide substantially water-tight joints, and a projecting rib-like means with an overhung portion mounted on the under side of the joiner shingle at a point adjacent the butt thereof, the upper edge of said joiner shingle being adapted to engage and lock with the projecting rib-like means on the next higher adjacent joiner shingle, the upper edge of said joiner shingle between said recesses being narrower than the body thereof, but at least as wide as said projecting rib-like means.

12. In a covering for a surface, the employment of substantially rectangular square cornered shingles laid in substantially spaced rows, the bottom of one overlapping the top of the next lower adjacent shingle in the row, each of said shingles being nailed in place across the top of a point which will be covered by the overlap of the next higher shingle; in combination with joiner shingles disposed in rows alternating with said shingles, for covering the spaces therebetween and completing the courses thereof, each joiner shingle having its upper corners recessed so as to produce an open upper corner profile adapted to receive the full size lower adjacent substantially square corners of the next higher course of shingles and permit said joiner shingle to overlap the side edges of the shingles in the same course, said joiner shingle extending below the bottom line of the shingles in the same course so as to provide a covered horizontal joint with the next lower joiner shingle and at the same time to eliminate exposed open vertical butted joints, receptacles on the upper end of said joiner shingle between said recesses adapted to receive a suitable means for fastening same to the surface being covered, and a projecting rib-like means mounted on the under side of the joiner shingle at a point adjacent to but spaced from the butt thereof, the length of said rib-like means being as a maximum equal to the distance between the substantially square cornered shingles to be joined in rows, said rib-like means having an overhung portion forming a socket at the edge thereof adjacent the butt of said joiner shingle, the upper edge of said joiner shingle between said recessed upper corners being formed so as to fit the socket of the rib-like means of the like next higher joiner shingle and lock therewith to hold the bottom of one joiner shingle against the top of the next lower joiner shingle when the substantially rectangular shingles and joiner shingles are laid in the prescribed manner.

CERTIFICATE OF CORRECTION.

Patent No. 2,135,811.

November 8, 1938.

BERT G. GOSLIN.

It is hereby certified that error appears in the printed specification of the above numbered patent requiring correction as follows: Page 4, first column, line 3, claim 3, strike out the word "water-tight" and insert the same before "means" in line 4, same claim; and second column, line 39, claim 8, for "rectangularly" read rectangular; page 5, second column, line 33, claim 12, for the word "of" read at; and that the said Letters Patent should be read with this correction therein that the same may conform to the record of the case in the Patent Office.

Signed and sealed this 31st day of January, A. D. 1939.

Henry Van Arsdale
